UNITED STATES PATENT OFFICE.

ZACHARIAH E. RICE, OF LANDISBURG, PENNSYLVANIA.

SAFETY.

Application filed June 8, 1922. Serial No. 566,299.

To all whom it may concern:

Be it known that I, ZACHARIAH E. RICE, a citizen of the United States, residing at Landisburg, in the county of Perry and State of Pennsylvania, have invented a new and useful Safety, of which the following is a specification.

This invention relates to fire arms and aims to provide novel means for indicating when a gun of the hammerless type is in its active or inactive position in respect to the triggers, so that a person using the fire arm can tell at a glance whether the triggers are locked or unlocked.

Another object of the invention is to provide a device of this character which may be readily and easily positioned on the usual firing action of a gun where the same may be automatically operated by the usual locking member of the gun.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a fragmental elevational view of a stock disclosing the invention in use.

Figure 2 is an elevational view of the usual movable member of the gun.

Figure 3 is a sectional view through the body portion of the device and disclosing the indicating means in its indicating position.

Figure 4 is a sectional view disclosing the body portion of the device, and showing the indicating means in its non-indicating position.

Figure 5 is a plan view of the button or indicating means.

Referring to the drawing in detail, the reference character 5 designates the stock of a gun which is of the usual construction, and which supports the usual firing action.

The reference character 6 designates the upper plate of a gun action over which operates the sliding locking member 7 which is formed with the usual depending arm 8, designed to contact with a locking lever for locking the firing mechanism out of operation.

An opening 9 is formed in the upper surface of plate 6, in which opening is positioned the head 8; the indicating spot being inlaid in the top of the same. The coiled spring 7' that encircles the stem 10 operates through a suitable opening in plate 6 constituting the indicating element of the device.

The locking member 7 in its operation, slides over the plate 6 from a position as indicated in Figure 1 of the drawings, to a position as indicated by Figure 4 of the drawing, to accomplish the locking and unlocking result of the firing mechanism. The sliding locking member is cut away as at 11 to receive the head 8', when the locking member is moved to a position to lock the triggers of the gun out of use.

Opening 12 is formed in the locking member 7 to permit the head 8' to be viewed therethrough, thereby indicating the position of the locking member 7, with respect to the triggers of the gun not shown.

Formed on the locking member 7 is a knurled thumb rest 13 to permit the operator to readily and easily slide the locking member 7 to accomplish its result.

Supported directly under plate 6 is a spring member 15 which has one end thereof secured to the plate as at 16, the opposite end thereof contacting with the arm 8 to normally hold the same, together with the locking member 7 against movement.

It might be further stated that a suitable coloring medium may be applied to the head 8' to allow the indicator to be readily viewed.

In the use of the device, it is obvious that when the locking member 7 is moved to a position as indicated by Figure 1 of the drawing, the locking member is operating to lock the triggers of the gun. The indicating head 8', being visible through the opening 12, indicates that the triggers are in their locked position, and the operator may, by moving the locking member to a position as shown by Figure 4, unlock the triggers.

Having thus described the invention, what is claimed as new is:

1. In combination with a gun stock, a plate supported thereon, a spring pressed indicating member supported by the plate, a sliding locking member supported over the plate and having an opening, said sliding locking member adapted to be moved to a position directly over the indicating mem-

ber, an arm forming a part of the sliding locking member, and a spring member contacting with the depending arm to restrict movement of the sliding locking member.

2. In combination with a gun stock, a plate supported on the gun stock, a spring pressed indicating member carried by the plate, a sliding locking member having an opening adapted to expose a portion of the indicating member, when the sliding locking member is moved to its active position, an arm forming a part of the sliding locking

member, a pin supported by the arm, and a spring member resting on the pin and adapted to exert a pressure on the arm to normally restrict movement of the sliding locking member.

In testimony that I claim the foregoing as my own, I have hereto affixed my signature in the presence of two witnesses.

ZACHARIAH E. RICE.

Witnesses:

Wm. C. LEBO,
PAUL G. SWARTZ.
